LINE MARKER
Bill W. Sorenson, Jefferson, Iowa
Filed Apr. 28, 1964, Ser. No. 79,715
Term of patent 14 years
(Cl. D14—3)

The dominant features of my design reside in the portions shown in full lines.

I claim:

The ornamental design for a line marker, substantially as shown and described.
